Serial No. 59,184

6 Claims. (Cl. 260—635)

1

This invention relates to the preparation of therapeutic products and, more particularly, to the preparation of erythritol, an intermediate in the preparation of tetranitrate of erythritol useful as a vasodilator in the treatment of heart ailments.

It has been proposed to prepare the tetranitrate of erythritol from butadiene by a long series of steps but such a method is very costly and requires skilled labor and expensive equipment.

We have now found that it is possible to obtain erythritol in excellent yield by reducing a dialkyl ester of tartaric acid under closely controlled conditions. When carrying out this process, in accordance with our invention, a solution of dialkyl ester of tartaric acid in a lower aliphatic alcohol is brought into contact with a suitable hydrogenation catalyst such as black copper-chromium oxide, and hydrogenated under high pressure of at least 3500 lbs. per square inch and at a temperature of about 125° to 200° C.

It is essential that the hydrogenation be carried out at a high pressure preferably of 5000 lbs. or more as almost no reaction will take place at 2000 lbs. pressure, or less. The reduction may be carried out at about 125 to 200° C. but the preferred range is 150—175° C. The lower temperature requires longer reduction periods while temperatures of 200° C. or more result in the hydrolysis of erythritol. It is equally essential to employ relatively large amounts of catalysts, preferably 50 to 100% by weight of the amount of ester used. High ratios of catalyst are necessary for obtaining high yields as the catalysts usually lose some of their activity during the process of hydrogenation.

The reaction may be represented by the following equation:

The following examples illustrate methods of carrying out the present invention, but it is to be understood that these examples are given by way of illustration and not of limitation.

EXAMPLE 1

Meso-tartaric acid was prepared from d-tartaric acid by means of hot alkali isomerization followed by the removal of the d- and l-isomers as the potassium salts and precipitation of lead meso-tartrate (Beilstein, III, 529, 4th ed., 1921).

2

Esterification of the lead salt was effected through the use of ethanolic hydrogen chloride. The crystalline diethyl meso-tartrate was isolated and purified. The purified ester melted at 54—56° C.

Black copper chromium oxide catalyst was prepared according to the procedure outlined on page 13 of Adkins, "Reactions of Hydrogen with Organic Compounds over Copper-chromium Oxide and Nickel Catalysts," the University of Wisconsin Press (1937).

The hydrogenation bomb used was made of alloy steel, capable of being heated and withstanding high pressures. The reaction mixture was placed in a copper liner, which was then placed in the bomb. To the bomb cap was attached a line from a source of high-pressure hydrogen and a pressure gauge. The temperature of the bomb contents was held constant by thermostatic control.

After carefully cleaning the copper liner, 2.5 gm. of the copper-chromium oxide catalyst, 5 gm. of diethyl meso-tartrate, and 107 cc. of absolute methanol were charged. Hydrogen gas was then introduced until a pressure of 3580 lbs. per square inch at 33° C. was attained. After standing one-half hour, the gauge reading remained the same, indicating the absence of leaks.

The temperature was then raised to 164° C. over a period of one hour, and a pressure of 5120 lbs. per square inch resulted. The temperature was maintained at 160—168° C. for four hours while the bomb was subjected to continuous shaking. The pressure varied from about 5000 to about 5100 lbs. per square inch. The temperature was allowed to drop to 130° C. over one hour, while shaking continued; the pressure dropped to 4520 lbs. per square inch. The bomb was then allowed to cool overnight to 29° C. without shaking, the pressure at this temperature was 3400 lbs. per square inch.

The bomb was then vented to release hydrogen, opened, and the contents were removed. The mixture was heated to boiling and filtered hot to remove the catalyst. The filtrate was concentrated on a steam bath to about 10 cc. and then was cooled and agitated to induce crystallization of meso-erythritol. A large volume of diethyl ether was added to complete the crystallization, and the solid was filtered and washed with ethanol and ether. There was obtained 1.8 gm. (60.8%) of meso-erythritol.

The combined filtrate and washings were evaporated to dryness on a steam bath, and 1.0 gm. of syrup remained. The syrup was dissolved in hot ethanol and cooled. An additional 0.15 gm.

3

of meso-erythritol crystallized, to give a total yield of 1.95 gm. (65.8%).

The combined filtrate and washings were evaporated to dryness on a steam bath, and 275 cc. of hot ethyl acetate were added. The solution cooled and an oil separated and was removed. The ethyl acetate layer was evaporated to dryness, and 0.2 gm. (4%) of unchanged diethyl meso-tartrate remained.

The oil layer was distilled in vacuo, and the fraction boiling at 80-100° C./10-4 mm. was collected. There was obtained 0.65 gm. (22%) of isomerized erythritol. Thus an overall recovery of 2.6 gm. (87.8%) of erythritol was obtained, and 0.2 gm. (4%) of unchanged starting material was recovered.

The meso-erythritol melted at 118-122° C., and a 10% solution in ethanol showed no rotation. Anal. Calc'd. for C₄H₁₀O₄: C-39.3; H-8.25. Found: C-39.9; H-8.18.

The isomerized erythritol was characterized as the dibenzal derivative: M. P. 216-218° C.; mixed M. P. with dibenzal d-erythritol 213-218° C.; mixed M. P. with dibenzal meso-erythritol (M. P. 195-198° C.) 185-186° C. Anal. Calc'd. for C₁₈H₁₈O₄: C-72.5; H-6.05. Found: C-72.8; H-6.2.

EXAMPLE 2

The following table shows the results of several experiments carried out under varying conditions and with varying starting materials.

Table

	Reactant	Solvent	Temp., °C.	Hydrogen press., lbs. per sq. in. at Reaction Temp.	Hydro- gena- tion time, hours	Wt. of catalyst +wt. of reactant	Per cent unre- acted starting Reactant	Nature and amount of products (based on starting reactant converted)
1	Dimethyl meso-tartrate	methanol	172	5,100	5.5	0.5	12.5	64.5% meso-erythritol (M. P. 120° C.); 32% isomerized erythritol syrup.
2	Dimethyl meso-tartrate	do	165	5,100	5.0	0.5	22.5	72% meso (M. P. 119° C.); 28% isomerized erythritol syrup.
3	Dimethyl meso-tartrate	ethanol	165	5,100	6.0	0.5	12	73% meso; 23% isomerized erythritol syrup.
4	Dimethyl meso-tartrate	methanol	165	2,000	6.0	0.5	100	No reduction; catalyst changed to red inactive form.
5	Diethyl meso-tartrate	do	165	5,100	4.5	0.5	10	62% meso (M. P. 121° C.); 35% isomerized erythritol syrup.
6	Diethyl d-tartrate	do	165	5,100	4.0	1.15	35	97% partially isomerized d-erythritol (M. P. 88-90° C.). ¹
7	Diethyl d-tartrate	do	165	5,100	5.75	0.5	46	98% partially isomerized d-erythritol (M. P. 87.5-88.5° C.). ²
8	Diethyl d-tartrate	do	165	5,100	5.0	1.0	20	65% partially isomerized d-erythritol (M. P. 87-88° C.); 15% isomerized erythritol syrup.
9	Diethyl d-tartrate	none	165	5,100	13.5	0.2	96	100% isomerized erythritol.

¹ $[\alpha]_{D}^{27}=3.9^{\circ}$ (6% solution in water). Accepted value for d-erythritol in water: $[\alpha]_{D}^{25}=4.3^{\circ}$.

² $[\alpha]_{D}^{27}=3.9^{\circ}$ (6% solution in water).

³ The catalyst specimen used in this experiment was the same specimen previously used for the reduction in experiment 6, above, and was merely washed with methanol between experiments.

Modifications may be made in carrying out the present invention without departing from the spirit and scope thereof and the invention is to be limited only by the appended claims.

We claim:

1. The process of preparing erythritol which comprises, reacting a solution of a dialkyl ester of tartaric acid in a lower aliphatic alcohol with hydrogen, said hydrogenation reaction being carried out at a temperature within the range of 125-200° C., and at a pressure of at least 3500 pounds per square inch in the presence of black copper-chromium oxide catalyst, said catalyst

being present in an amount in excess of about 50% by weight of said tartaric acid ester, and recovering erythritol from the resulting mixture.

2. The process of preparing erythritol in high yields by hydrogenation of tartaric acid esters, which comprises, subjecting a solution of an ester of tartaric acid selected from the group consisting of dimethyl tartrate and diethyl tartrate in a lower aliphatic alcohol selected from the group consisting of methyl alcohol and ethyl alcohol to the action of hydrogen, said hydrogenation reaction being carried out at a temperature within the range of 125-200° C., and at a pressure of at least 3500 pounds per square inch in the presence of black copper-chromium oxide catalyst, said catalyst being present in an amount in excess of about 50% by weight of said tartaric acid ester, and recovering erythritol from the resulting mixture.

3. The process of preparing erythritol in high yields by hydrogenation of tartaric acid esters, which comprises, subjecting a solution of an ester of tartaric acid selected from the group consisting of dimethyl tartrate and diethyl tartrate in a lower aliphatic alcohol selected from the group consisting of methyl alcohol and ethyl alcohol to the action of hydrogen, said hydrogenation reaction being carried out at a temperature within the range of 150°-175° C., and at a pressure of at least 3500 pounds per square inch in the presence of black copper-chromium oxide catalyst, said catalyst being present in an

amount in excess of about 50% by weight of said tartaric acid ester, and recovering erythritol from the resulting mixture.

4. The process of preparing erythritol in high yields by hydrogenation of tartaric acid esters, which comprises, subjecting a solution of dimethyl tartrate in a lower aliphatic alcohol selected from the group consisting of methyl alcohol and ethyl alcohol to the action of hydrogen, said hydrogenation reaction being carried out at a temperature within the range of 150°-175° C., and at a pressure of at least 3500 pounds per square inch in the presence of black copper-

chromium oxide catalyst, said catalyst being present in an amount equivalent to about 50-100% by weight of the weight of said dimethyl ester of tartaric acid, and recovering erythritol from the resulting mixture.

5. The process of preparing erythritol in high yields by hydrogenation of tartaric acid esters, which comprises, subjecting a solution of diethyl tartrate in a lower aliphatic alcohol selected from the group consisting of methyl alcohol and ethyl alcohol to the action of hydrogen, said hydrogenation reaction being carried out at a temperature within the range of 150°-175° C., and at a pressure of at least 3500 pounds per square inch in the presence of black copper-chromium oxide catalyst, said catalyst being present in an amount equivalent to about 50 to 100% by weight of the weight of said diethyl ester of tartaric acid, and recovering erythritol from the resulting mixture.

6. The process of preparing erythritol in high yields by hydrogenation of tartaric acid esters, which comprises, subjecting a solution of diethyl-meso-tartrate in a lower aliphatic alcohol selected from the group consisting of methyl alcohol and ethyl alcohol to the action of hydrogen, 25

said hydrogenation reaction being carried out at a temperature within the range of 150°-175° C., and at a pressure of at least 3500 pounds per square inch in the presence of black copper-

5 chromium oxide catalyst, said catalyst being present in an amount equivalent to about 50 to 100% by weight of the weight of said diethyl-meso-tartrate, and recovering meso-erythritol from the resulting mixture.
